UNITED STATES PATENT OFFICE

JOHN A. NITCHIE, OF ELM CREEK, NEBRASKA.

GEARING.

1,087,177.

Specification of Letters Patent. Patented Feb. 17, 1914.

Application filed December 12, 1912. Serial No. 736,380.

To all whom it may concern:

Be it known that I, JOHN A. NITCHIE, a citizen of the United States, residing at Elm Creek, in the county of Buffalo and State of Nebraska, have invented a new and useful Gearing; and I do hereby declare the following to be a full, clear, and exact description of the invention, such as will enable others skilled in the art to which it appertains to make and use the same.

This invention relates to a new and useful differential gear drive for automobiles, including connections between it and an engine for transmitting power thereto, and further including controlling means for both the power transmission and the differential gearing.

It is an object of the invention to improve, simplify and render more efficient the general construction of such differential gearing, power transmission and control mechanism, in order to obtain better and more advantageous results.

There are disclosed in the drawings certain features of construction, but in practical fields these features may necessitate alterations, to which the patentee is entitled, provided the alterations fall within the scope of what is claimed.

The invention comprises further features and combination of parts, as hereinafter set forth, shown in the drawings and claimed.

In the drawings, Figure 1 is a view in side elevation showing the improved differential gearing, the power transmission mechanism and the control therefor constructed in accordance with the invention. Fig. 2 is a sectional view. Fig. 3 is a plan view showing the casing for the gearing partly in section. Fig. 4 is a vertical sectional view through the gearing. Fig. 5 is a sectional view on line 5—5 of Fig. 2. Fig. 6 is a sectional view transversely through the controlling mechanism. Fig. 7 is a sectional view on line 7—7 of Fig. 6.

The differential gearing.—Referring more particularly to the drawings 1 designates the casing, which is annular in contour, and provided with an offset casing 2, the cover plate 3 of which is bolted in place as at 4. Projecting outwardly from the cover plate is a frame 5 having an elongated bearing 6 for the reception of a portion of the power transmission shaft 7. This portion 7 of the

power transmission mechanism at its rear end is rectangular in cross section, and is mounted in a bearing 8 of the casing of the said gearing. In other words, the bearing 8 is connected to a central partition wall 9 of said casing.

The casing 1 is provided with a pair of cover plates 9^a and 10 having tubular shafts 11 and 12. These cover plates are bolted in place as shown at 13. The shafts 11 and 12, which are tubular or hollow receive loops 14 of the usual springs 15, which connect between the body 17 of the vehicle and the said tubular shaft. The tubular shafts 11 and 12 are reinforced relative to the frame 5, by means of the brace rods 18.

Mounted in a bearing of the partition wall 9 and in the tubular shafts are the usual drive axles or shafts 20^a and 20^b, on the outer ends of each of which the rear wheels 21 of the vehicle are mounted. Fixed to rotate with the drive axle 20^b is a bevel gear 22, arranged on the right hand side of the partition wall 9, reference being had to Fig. 3. On the left hand side of the partition wall 9, reference being had to Fig. 3, 80 and loosely mounted upon the drive axle 20^b is a gear 24 having two sets of teeth 25 and 26, the teeth 25 being nearer the axle, while the teeth 26 are located at a considerable distance from the drive shaft or axle 20^b. The gear 24 is provided with a casing, connected to the gear as at 27. This casing 28 incloses a gear 29, which is fixed upon the drive shaft or axle 20^b, and which is designed to mesh with the pinions 30. These 90 pinions 30 are mounted upon stub shafts 31 which are mounted in bearings of said casing. Relative to the drive axle or shaft 20^b, the stub shafts are arranged radially. The pinions 30 mesh with a gear 32, which is 95 keyed to the drive axle or shaft 20^b.

Slidably mounted upon the rear portion 7 of the power transmission shaft, which portion is rectangular in cross section, are three pinions 33, 34 and 35. The pinion 33 is 100 adapted to be thrown in mesh with the teeth 26 of the gear 24, in order to rotate the drive axles or shafts and the rear automobile wheels at low speed, while the gear 35 is adapted to be thrown in mesh with the teeth 25 of the gear 24, in order to impart high speed to the drive shafts 20^a and 20^b and the automobile wheels; whereas the pin-

ion 34 is adapted to be thrown in mesh with the gear 22, for reversing the drive shafts or axles in its movements.

The frame 5 is provided with a pair of 5 bearings 37 and 38, secured in place by the bolts 39. Mounted in these bearings 37 and 38 are three rods 40, 41 and 42, which terminate at their rear ends in laterally extending forks 43. The fork of the rod 40 embraces a 10 grooved portion 44 of the pinion 33, whereby the pinion may be adjusted upon the rear portion 7 of the power transmission shaft, so as to throw it in mesh with the teeth 26, while the fork of the rod 42 embraces a 15 grooved portion 45 of the pinion 35, whereby the said pinion 35 may be thrown in mesh with the teeth 25 of the gear 24, for obtaining high speed; whereas the fork of the rod 41 engages a grooved portion of the 20 pinion 34, in order to shift the said pinion 34 in mesh with the gear 22, whereby the drive shaft or axle 20 may be reversed in its movements. However, only one of the pinions 33, 34 and 35 may be shifted at a time.

25 *Power transmission mechanism.*—Referring more essentially to the power transmission mechanism, it will be seen that the frame 5 at its forward end terminates in laterally extending offset ears 47, which are 30 pivoted upon the studs of the ears 48, which form a part of the plate 49. This plate 49 is bolted at 50 to the transverse plate 51 of the frame of the machine. The plate 51 is provided with an upstanding portion 53, in 35 which a threaded shank of coil spring 54 is mounted. Threaded upon the shank 53 is a nut 56, for adjusting the shank in position relative to the upstanding portion of the said plate 52. Arranged forwardly of the 40 plate 51 and secured to the frame 17 is an angular bar 58. Mounted in bearings 59 of the plate 51 and the bar 58 is the intermediate portion 60 of the power transmission shaft, the end 61 of which is provided with 45 a universal coupling 62 connecting with the portion 7 of said power transmission shaft, while the end 63 of said intermediate portion 60 has keyed thereto a friction cone 64. This friction cone is constructed with a 50 grooved portion 65, which is embraced by the forked end 66 of a rod 67. This rod 67 is mounted slidably in a bearing 68, which is bolted or otherwise secured to the bar 58. The end 69 of the rod 67 is connected to the 55 coil spring 54. When the rod 67 is shifted, in order to shift the cone 64 (which constitutes a clutch member) telescopically into the clutch member 70 of the engine shaft 71, the coil spring 54 is put under tension, so 60 that when pressure is relieved upon the rod 67, the spring will return said rod to its initial position. The engine shaft is mounted in bearings 72 and 73, while the engine (which is only outlined in elevation) may be 65 of any conventional form or construction.

Controlling mechanism.—Referring more especially to the controlling mechanism, it will be observed that the frame 17 is provided with a plate bracket 75, bolted to the frame as at 76, and formed into a bearing 77, in which the telescopically arranged shafts 78, 79 and 80 are mounted. The shaft 78 at one end is provided with a downwardly extending arm 81, to which a bar 82 is connected. The end 83 of this bar 82 is connected to the rod 41, in order that when the shaft 78 is rocked, the rod 41 will be reciprocated, for shifting the pinion 34, in order to reverse the movement of the drive shaft or axle 20, and its attendant parts. The tubular shaft 79 at one end is provided with a downwardly extending arm 84, and connected to it, at one of its ends is a bar 85, which in turn connects pivotally to the rod 40 in order to shift the pinion 33, for adjusting the differential gearing for low speed. Further, the tubular shaft 80 is also provided with a downwardly extending arm 87. Connected to the arm 87 is a bar 88. The end 89 of the bar 88 is pivotally connected to the rod 42, whereby the pinion 35 may be shifted, so as to operate the drive shaft or axle 20 at high speed. Also journaled in the roll bearing 77 is a tubular shaft 90, through which the shafts 78, 79 and 80 telescope. This shaft 90 at one end is provided with an arm 91, which has a slot and pin connection 92 with the rod 67. The other end of the shaft 90 is provided with an upwardly and forwardly extending arm 93, laterally from which another arm 94 projects. This arm 94 is disposed in the path of the low, high, and reverse speed levers 96, 97 and 98, so that when any one of said levers is operated for changing the 95 gearing, the shaft 90 will be rocked, in order to throw the clutch connections between the intermediate portion 60 of the power transmission shaft and the engine section of said shaft, in gear, whereby the power shaft may be operated.

The lever 96 is carried by the shaft 79, while the lever 97 is carried by the shaft 80, whereas the lever 98 is carried by the shaft 78. These levers 96, 97, and 98 are provided with the usual dogs 99, which are designed to be operated by the usual hand grips 100, so as to coöperate with the rack quadrants 101. These quadrants are constructed relative to one another in order to form a frame 102, bolted or otherwise secured to a bracket plate 103, which projects laterally from the frame 17. The hand grips are connected to the dogs 99 by the rods 104. Also bolted or otherwise secured to the bracket plate 103 is a plate 106, one side of which is formed into a series of sleeves 107. One of the end sleeves is formed with a transverse bar 108. Mounted in each sleeve is a ball bearing 109. Threaded in an upturned flange 110 of the 110

bracket plate 103 is a screw member 111, which is provided at one end with a head 112 whereby the screw may be rotated, while the other end of the screw has swiveled to it a device 113, provided with a yieldable member 114, adapted to bear yieldably against one of the end ball bearings, so as to hold the ball bearings in place, the other end ball bearing against the bar 108. When one or the other of the levers 96, 97 and 98 is operated, it moves between the sleeves 107, thereby engaging between the balls, which are adjusted and held yieldably by the yieldable device only sufficiently to admit one of the levers 96, 97 and 98 at a time between said balls, thereby preventing the gearing from being changed to low speed, until after the high speed is cut out, or to reverse speed, until either the low or high speed is cut out, and vice versa.

From the foregoing, it will be ascertained, that an improved, efficient, cheaper and more advantageous gearing, including a power transmission mechanism, and a control mechanism for both have been devised, and one which has been found practicable.

The invention having been set forth, what is claimed as new and useful is:—

1. In a device of the kind described, a power transmission device including a series of bodily movable gears, a series of levers each arranged to move a separate gear of said series, a series of spaced and alined sleeves between which said levers can move, balls mounted in said sleeves and arranged to close the remaining spaces between the

sleeves when either of said levers is moved to position between adjacent sleeves, and means to hold said balls yieldably together.

2. In a device of the kind described, a power transmission device including a series of bodily movable gears, a series of levers each arranged to move a separate gear of said series, a series of spaced and alined sleeves between which said levers can move, balls mounted in said sleeves and arranged to close the remaining spaces between the sleeves when either of said levers is moved to position between adjacent sleeves, means to hold said balls yieldably together, and other means to adjustably limit the movement of said balls.

3. In a device of the kind described, a power transmission device including a series of bodily movable elements and a clutch having a movable member, levers each arranged to move one of said elements, a lever in the paths of said first lever and arranged to be moved in one direction by the movement of either of the first levers in the same direction, the last mentioned lever being arranged to move the clutch member, and means operated by the movement of any one of the first levers to lock all the remaining levers from movement.

In testimony whereof I have signed my name to this specification in the presence of two subscribing witnesses.

JOHN A. NITCHIE.
